UNITED STATES PATENT OFFICE.

GEORGE H. FORSYTH, OF CHICAGO, ILLINOIS.

METAL WINDOW-SASH.

945,225.

Specification of Letters Patent. Patented Jan. 4, 1910.

Application filed December 23, 1904. Serial No. 238,146.

To all whom it may concern:

Be it known that I, GEORGE H. FORSYTH, a citizen of the United States, residing at Chicago, in the county of Cook and State 5 of Illinois, have invented certain new and useful Improvements in Metal Window-Sash, of which the following is a specification.

This invention has to do with window 10 sash, but more especially metal sash.

One of the objects of my invention is to provide a sash of the latter type, in which members of the sash proper shall be resili- 15 ent so as to have spring-pressed engage- ment with the coöperating guides of the window casing, whereby dust is excluded and the sash is prevented from rattling.

I also provide means for adapting the sash to varying widths of opening of window casings.

I also provide a simple means for holding the glass securely within the opening of the sash.

Referring to the drawings,—Figure 1 is 25 a front elevational view of the sash, pro- vided with a spring counterbalance; Fig. 2 is a fragmentary front elevational view of the sash having a modified form of spring balance; Fig. 3 shows details of a means for 30 fastening the upper end of the spring balance in Fig. 1 to the casing; Figs. 4, 5, 6, 7, 8, 9, 10, 11 and 12 are detail views show- ing various means for adapting the sash to 35 varying widths of window casing; Figs. 13 to 16 show various means for holding the glass in the sash and providing spring-pressed engagement between the guiding members of the sash and the coöperating guides of the window casing; Fig. 17 is an 40 end view of the vertical guide showing one way of finishing same, by relatively off- setting the lipped over ends; Fig. 18 is a sec- tional view showing the offsetting of the 45 ends in further detail. Fig. 19 is a cross- sectional detail through the lower bar of the sash and the lower portion of the glazing.

1 is the window casing, 2 and 3 the cross members, and 4 the vertical members of the 50 sash. The sash members are joined at their corners by the extensions 6 of the back walls of the vertical members being lipped over and riveted to the back walls of the cross members; and by the extended sides 7 55 of the cross members entering within and being riveted to the ends of the vertical

members. The extensions 7 are bent in- wardly as shown in Fig. 17, whereby the vertical and cross members of the sash present an even surface.

5 is the glass, which is held in position within the sash.

8 is the actuating spring of the sash balance, which contains the rods 9 and 10. The latter are lipped over at their respective ends so as to connect the spring at one end to the sash and at the other end to the window casing. The rod 9 engages the sash through its hook 11 which passes around a pin 12 carried by the bracket 13, which is 70 shown as riveted to the rear walls of the vertical and cross members of the sash. The rod 10 has a hook 14 adapted to engage the pin 15, which is carried by the bracket 16, as shown in Fig. 3, the bracket being fas- 75 tened to the window casing by the screw 17.

The upper portion of the vertical member of the sash is preferably provided with a recess 18, which permits a key 19, after being inserted through the hook 14, to be 80 held in a position ready for releasing the hook and allowing the latter to drop and engage the pin 15. This arrangement permits connection of the sash balance between the sash and the window casing after the sash 85 has been introduced in position within the window casing. The ends of the vertical members of the sash are preferably turned over as at 20, presenting two overlapping lips 21 and 22 as shown in Fig. 17 and 90 Fig. 18.

In Fig. 2 I have shown a modified form of sash balance, in which 23 is a plate fastened to the inner wall of the vertical member and provided with a tongue 24 adapted to 95 operate within the slot of the tube 25, containing the actuating spring 8. The tube 25 is provided with a base plate 26, which is fastened to the bottom of the window casing.

It must be evident that in either construc- 100 tion, the springs are under their greatest tension when the windows are down, and that through their tendency to extend, they overcome in a greater or less degree, ac- cording to their strength, the weight of the window, thereby enabling the latter to be readily raised to any desired position.

27 is a lock member carried by the sash and 28 a stationary member fastened to the 110 casing whereby the sash may be locked if desired in any adjusted position.

In the various figures showing sectional

views of the vertical members of the sash, it should be carefully noted that the distance between the engaging surfaces of these vertical members differs when the sash is withdrawn from engagement with the guides of the window casing from what it is when the sash is in operation within the window casing.

In Fig. 16 I show a protruding guide 29, of the window casing, and in this case the vertical member, when withdrawn from engagement therewith is transversely narrowed or diminished in width, which causes the said vertical member, upon engaging the guide, to be expanded laterally under tension. In the other figures and in my preferred form of construction, the vertical guide flares outwardly so that, when withdrawn, the distance between its engaging surfaces is greater than the inner width of the groove 30, whereby when the sash is introduced within the latter, frictional engagement is established between the two. If a metal sash were provided with transversely yieldable guides the distance between whose contacting surfaces was the same when associated with and disassociated from the casing guide, a spring-pressed fit would be impossible unless such engagement were established by contacting the width of the groove in the window casing and thereby the outer edges of the vertical guides of the sash, which would distort the even bearing of the latter, making a line engagement and preventing a uniform surface engagement between the outer portions of the vertical members and the guides of the window casing. In my preferred construction, however, the inner width of the groove in the casing is such that when the vertical guide is introduced therein the co-operating surfaces will uniformly contact each other throughout their depth of engagement, thereby most efficiently excluding the dust and preventing rattling of the window. In some forms of construction shown I have illustrated the grooves of the window casing as being made by the side walls being integral with the rear portion thereof, while in other forms I make a groove by making either one or both of the side walls detachable from the rear portion thereof.

In Figs. 4, 5, 6, 7, 8, 9, 10, 11 and 12, I show various means for adapting the sash to varying widths of the window casing; the distance between the guides of window casings, which guides normally consist of grooves, varying considerably. This variation is easily allowed for in the case of wooden sash by planing off the vertical edges of the window sash, whereas in metal sash this would be expensive and extremely difficult, and in some cases even impossible, and would at least probably involve defacement

of the paint applied to the sash. It is my intention, therefore, to make a metal sash of substantially such a width that its outer edges will come approximately mid-way of the depth of the grooves in the window casing of correct width. If the distance between the bottoms of the grooves in the casing were greater relatively to the width of the sash, it must be evident that there would be danger of the sash being withdrawn from the groove first from the one side and then from the other. To prevent this, I preferably lip over one or both of the outer edges of the vertical members and provide grooves either with separate or integral co-operating lips. These lips tend to interlock with each other, and prevent the sash from being accidentally withdrawn from the window casing. I have shown the grooves in window casings made of metal as well as wood or other suitable material. In my preferred form I make at least one side wall of the groove detachable and where the engaging lips are not integral therewith, I also prefer to make the latter detachable from the window casing.

In Fig. 10 I have shown only one engaging lipped member fastened to the casing, but it must be evident that if desired, two could be employed, one on either side of the groove. It should be noted that in Fig. 10, the member 31 inclines toward the side wall of the groove, whereby its lip 32 strikes said wall of the groove before the sash is introduced. After the sash has been introduced within the groove and the stop 33 has been screwed into position not only do the vertical members at 34 bear against the sides of the groove under tension, but the lip 32 of the metal strip 31 bears against the inner surface of the vertical sash member, as indicated in dotted lines, whereby the entrance of dust is prevented.

In the various figures above mentioned which show the lipped edges of the vertical members engaging with the co-operating lipped locking members of the casing guide, I preferably have the said locking members so formed as to engage the sides of the vertical members under tension, although it is understood that this is not essential.

In Fig. 9, I not only lip over the outer edges of the vertical sash members but give them a backward turn to co-operate with the correspondingly lipped over and backwardly turned members of the guides of the window casing, whereby a still greater closeness of engagement is effected. In Fig. 12 I show this arrangement of interlocking of sash and casing members, in the case of a sash whose vertical members are not of necessity transversely movable.

In Figs. 13, 14, 15, 16 and 19 I show various constructions of metal strip for holding the glass within the sash. These strips

are in all cases not integral with the sash members but separate members and hold the glass under spring pressure. In the construction shown in Figs. 13, 14 and 15 these strips consist of single pieces and are adapted to be moved in the plane of the sash members, after the glass has been introduced, whereby the more readily to engage the glass. In Figs. 13 and 14 these strips are adapted to be moved inwardly and outwardly of the glass.

In order to introduce the glass the strips 35 are retracted, after which they are thrust forward and either held in engagement with the glass by means of screws 36 or by a rotary key 37. The latter is operated by means of a spindle 38 which is carried by the bearing 39, the latter being formed by a strip of metal bent and fastened to the rear wall 40 of the vertical member. The key may be operated by means of a screw-driver used in connection with the slot 41 in the end of the spindle 38.

In Fig. 15 the glass, after being inserted, is engaged by the strip 42, by introducing the latter through the ends of the sash. The V-ways 43 in the sash members hold the engaging portions 44 of the strips 42.

In Fig. 19 I show a means whereby the glass may be inserted within the top and bottom glass-engaging strips without the latter being moved relatively to the sash members themselves. The glass, as indicated in the dotted lines, is first inserted within the top strip 45 and is raised up as far as possible. The inside depth of the strip 45 is such that the glass may thereupon be swung, as indicated in the dotted lines, into position and inserted within the lower engaging strip 46. In all the forms of engaging strips shown I preferably form them so that they will positively grip or engage the glass under constant tension, thereby preventing rattling of the latter.

In Figs. 17 and 18 I show a manner of lipping over the ends of the vertical members of the sash so that the interior thereof will not be visible when the sash is in position within the window casing.

I claim:

1. In a window construction, the combination with a sash member having transversely elastic frame-engaging sides, of a casing having a guide coöperating with said sides, said sides, when disengaged from the guide, having their guide-engaging surfaces separated by a distance different from the width of the guide.

2. In a window construction, the combination with a sash stile having frame-engaging sides that are elastically movable toward and from each other, of a casing having a guide adapted to coöperate with said sides, said guide being of a width different from the distance between the guide-engaging sur-

faces of said frame-engaging sides when said parts are separated, substantially as described.

3. In a window construction, the combination with a sash member having transversely elastic sides, of a casing having a guide adapted to engage said sides throughout substantially the extent of their overlapping surfaces, said sides, when separated from said guide, having their guide-engaging surfaces separated a distance greater than the width of said guide.

4. In a window construction, the combination with a sash having an integral frame-engaging member provided with transversely separated sides, of a casing having a guide adapted to coöperate with said sides, said guide and sides being of different widths between their coöperating surfaces, when separated, whereby said sides are spring-pressed into engagement with said guide.

5. A metal sash having an elastic stile provided with contacting surfaces adapted to engage coöperating surfaces of a guide of the window casing, the distance between said contacting surfaces of the sash stile being different when the sash is engaged with and separated from the casing, whereby the sash contacts the casing guide under spring tension throughout substantially the extent of the overlapping surfaces, substantially as described.

6. In a window construction, the combination with a sash member having transversely elastic frame-engaging sides, of a casing having a groove coöperating with said sides, said groove being narrower than the width between said sides when the latter are separated therefrom, whereby said sides engage the walls of said groove under spring pressure.

7. In a window construction, the combination with a metal window sash member having transversely elastic frame-engaging sides, of a casing having a groove coöperating with said sides, said groove being narrower than the width between said sides when the latter are separated therefrom, whereby said sides contact the walls of said groove under spring pressure throughout the extent of their overlapping surfaces.

8. In a window construction, the combination with a sash member having transversely elastic frame-engaging sides unitary with said sash member, of a casing having a groove coöperating with said sides, said groove being narrower than the width between said sides when the latter are separated therefrom, whereby said sides have spring-pressed surface contact with the walls of said groove.

9. A window sash having frame-engaging members comprising each a pair of separated sides transversely elastic toward and from each other, the vertical and horizontal mem-

bers being united by joints which preserve the elasticity of said sides throughout substantially their entire length and depth.

10. A window sash having frame-engaging members comprising each a pair of separated sides transversely elastic toward and from each other, the vertical and horizontal members being united by overlapping parts so arranged as to preserve the elasticity of said sides throughout substantially their entire inner depth.

11. A metal window sash having frame-engaging members comprising each a pair of separated sides transversely elastic toward and from each other, the vertical and horizontal members being united at their ends by integral overlapping parts so arranged as to preserve the elasticity of said sides throughout substantially their entire depth.

12. A window sash having frame-engaging members comprising each a pair of separated sides transversely elastic toward and from each other, the vertical and horizontal members being united at their ends by integral overlapping parts so disposed as to cause the exposed surfaces of adjacent parts to lie flush.

13. A window sash having frame-engaging members comprising each a pair of separated sides transversely elastic toward and from each other, the vertical and horizontal members being united at their ends by integral overlapping parts so disposed as to cause the exposed surfaces of adjacent parts to lie flush and to preserve the elasticity of said sides at their joints throughout substantially their entire depth.

14. The combination with a window casing provided with guides, of a metal sash having a width different from that between the transverse surfaces of said casing guides, the said sash and casing guides having interlocking members adapted to prevent displacement of the sash from the casing.

15. The combination with a grooved window casing, of a sash having a width less than the distance between the bottoms of opposite grooves, said sash and groove being provided with interlocking members adapted to prevent displacement of the former from the latter.

16. The combination with a grooved window casing, of a sash having a width less than the distance between the bottoms of opposite grooves, said sash and groove being provided respectively with overlapping members coöperating to prevent displacement of said sash from the groove.

17. The combination with a window casing having grooved guides, of a metal sash having guide members integral with the sash, the distance between the said guide members of the sash being less than the distance between the bottoms of the casing

guide grooves, the latter and the guide members of the sash having interlocking members whereby to prevent displacement of the sash.

18. The combination with a window casing having grooved guides, of a metal sash having transversely elastic guide members integral with the sash, the distance between the said guide members of the sash being less than the distance between the bottoms of the casing guide grooves, the latter and the sash guides having interlocking parts whereby to prevent displacement of the sash.

19. The combination with a grooved window casing, of a sash having a width less than the distance between the bottoms of opposite grooves, said sash and groove being provided with oppositely extending overlapping lateral projections which coöperate to prevent displacement of the sash from the groove.

20. The combination with a window casing having sash guides, of a sash having a width less than the distance between the bases of the guides, one or both of said guides and the sash having coöperating members lying at an angle to the plane of the sash preventing edgewise displacement of the sash from the guide.

21. The combination with a window casing having sash guides, of a sash having a width less than the distance between the bases of the guides, one or both of said guides and the sash having coöperating members lying at an angle to the plane of the sash preventing edgewise displacement of the sash from the guide, said sash being capable of edgewise movement toward and from the bases of the guides.

22. The combination with a grooved window casing, of a sash having a width less than the distance between the bottoms of opposite grooves, said sash and groove being provided with coöperating sash-retaining devices, of which that carried by the groove engages the sash under tension.

23. The combination with a grooved window casing, of a metal sash having a width less than the distance between the bottoms of opposite grooves, said sash having groove-engaging guides integral therewith, and said guides and groove being provided with coöperating retaining devices, of which that carried by the groove engages the sash guide under tension.

24. The combination with a grooved window casing, of a sash having a width less than the distance between the bottoms of opposite grooves, said groove having a sash-retaining member detachably secured to a wall thereof.

25. The combination with a grooved window casing, of a metal sash having an elastically yieldable groove-engaging member and of a width less than the distance be-

tween the bottoms of oppositely disposed grooves, the groove having a retaining member adapted to engage said groove-engaging member under tension.

5 26. The combination with a grooved window casing, of a metal sash having a transversely yieldable stile and of a width less than the distance between the bottoms of the oppositely disposed grooves, the groove having a sash-retaining member adapted to engage the sash stile under tension.

10 27. A sash having a yieldable frame-engaging member movable therewith, in combination with a coöperating guide-groove normally permitting yielding movement of said frame-engaging member.

15 28. A sash having a yieldable frame-engaging member movable therewith, in combination with a coöperating guide-groove engaged by said frame-engaging member under spring tension.

20 29. A sash having a transversely elastic stile, in combination with a casing having a guide-groove engaged by said stile and permitting transverse yielding thereof.

25 30. A sash having a casing-engaging member transversely elastic throughout substantially its entire depth, in combination with a casing having a guide-groove engaged by said member and permitting transverse yielding thereof.

30 31. A sash having a stile transversely elastic throughout substantially its entire depth, in combination with a casing having a guide-groove engaged by said stile and permitting transverse yielding thereof.

35 32. The combination with a sash, of top and bottom glass-retaining strips secured to the top and bottom bars of the sash, and side retaining strips movable toward and from the side edges of the glass.

40 33. In a sash, a frame-engaging member comprising a pair of transversely elastic sides having their ends at an end of the sash overlapped and relatively offset to permit movement of said overlapped ends toward and from each other.

45 34. A sash stile the sides of which terminate adjacent to their outer margins in transversely yieldable and unsupported portions adapted to engage a guide of the window casing, the distances between the contacting surfaces of the stile and the casing guide being different when the stile and the casing guide are separated and engaged, whereby the stile engages the casing guide under spring tension.

50 35. In a metal window construction, the combination with a sash guide, of a hollow sash member the distance between whose guide-engaging surfaces when engaged with the guide is different from the distance between said surfaces when disengaged from the guide.

55 36. In a metal window construction, the

combination with a sash guide, of a hollow metal stile the distance between whose guide-engaging surfaces when engaged with the guide is different from the distance between their surfaces when disengaged from the 70 guide.

37. In a metal window construction, the combination with a sash guide, of a hollow sash member transversely elastic throughout substantially the entire depth thereof, the 75 distance between the guide-engaging surfaces of said hollow sash member when the same is engaged with the guide being different from the distance between said surfaces when disengaged from the guide. 80

38. In a window construction, the combination with a sash member, of an integral guide therefor, the relative distances between the guide-engaging parts of said sash member and between the sash-engaging parts 85 of said guide varying according as the sash member and guide are engaged or disengaged.

39. In a metal window construction, the combination with a sash guide, of a guide-engaging member of the sash, the guide-engaging parts whereof are normally unobstructed against lateral movement when engaged with said guide. 90

40. In a metal window construction, the combination with a window casing having sash guides, of a sash of less width than the distance between the bases of said guides, the guide-engaging parts of said sash being normally unobstructed against lateral movement when engaged with said guides. 100

41. The combination with a sash, of a glass-retaining strip movable edgewise in the plane of the sash and adapted to be retracted wholly within a frame member of the latter 105 whereby to permit frontwise insertion of the glass in the sash frame.

42. The combination with a sash, of a transversely elastic glass-retaining strip adapted to engage the glass under spring tension, said strip being movable edgewise in the plane of the sash and adapted to be retracted wholly within a frame member of the latter whereby to permit frontwise insertion of the glass in the sash frame. 110

43. The combination with a window casing having sash-guides, of a sash of a width different from the distance between the opposed transverse surfaces of the guides and movable edgewise between the latter, and means between the sash and one of said guides serving to prevent displacement of the sash from the sash opening and removable to permit frontwise insertion or removal of the sash. 115

44. The combination with a window casing having sash guiding grooves, of a sash of a width less than the distance between the bottoms of the guide-grooves, a detachable stop forming a side wall of a guide- 120

125

130

groove, and a sash-retaining member between the sash and the groove.

45. The combination with a window casting having sash-guiding grooves, of a sash of a width less than the distance between the bottoms of the guide-grooves, a detachable stop forming a side wall of a guide-groove, and a sash-retaining strip between the sash

and the groove, there being relative movement between said strip and the sash in the plane of the latter.

GEORGE H. FORSYTH.
